DESIGN FOR AN ALARM CLOCK

Joseph A. Hill, Chicago, Ill., assignor to William
M. Klompus, Chicago, Ill.

Application November 15, 1945, Serial No. 123,794

Term of patent 7 years

(Cl. D42—8)

To all whom it may concern:

Be it known that I, Joseph A. Hill, a citizen of the United States, residing at Chicago, county of Cook, and State of Illinois, have invented a new, original, and ornamental Design for an Alarm Clock, of which the following is a specification, reference being had to the accompanying drawings, forming a part thereof.

In the drawings:

Fig. 1 is a perspective view of an alarm clock embodying my new design.

Fig. 2 is a front elevation of the same.
Fig. 3 is a side elevational view.

The surface shading is intended to indicate contrasting tones or colors for the several parts.

I claim:

The ornamental design for an alarm clock, substantially as shown and described.

JOSEPH A. HILL.
